United States Patent Office

Des. 225,070
Patented Nov. 7, 1972

225,070

BICYCLE EXERCISER

Richard I. Proctor, 3201 Orange Grove Ave.,
North Highlands, Calif. 95660

Filed Apr. 12, 1971, Ser. No. 133,465

Term of patent 14 years

Int. Cl. D21—02

U.S. Cl. D34—5

Fig. 1

Fig. 3

Fig. 2

FIG. 1 is a perspective view of a bicycle exerciser, showing my new design, the view from the opposite side being substantially similar in appearance;

FIG. 2 is a front elevational view; and,

FIG. 3 is a top plan view.

I claim:

The ornamental design for a bicycle exerciser, as shown and described.
